METHOD OF REFRIGERATION

Harry Y. Stebbins, Los Angeles, Calif., assignor
to General American Precooling Corporation,
Chicago, Ill., a corporation of Delaware

Application June 12, 1940, Serial No. 340,191

3 Claims. (Cl. 62—24)

My invention relates to a method of, and apparatus for, precooling enclosures, more especially commercial transportation vehicles, such as for example, railway cars and commercial trucks prior to the commencement of their transport, containing perishable articles, such as for example and more particularly, though not exclusively, such articles of food as are deleteriously affected by the dehydrating effect thereon of refrigeration, as for example, asparagus, carrots, cauliflower, peas, celery, lettuce, artichokes, and spinach.

More particularly my invention relates to the precooling of articles involving the introduction into the enclosure for the articles, as for example in the case of a freight car through a side door opening thereof from a refrigerating apparatus, as for instance a portable refrigerating unit, disposed adjacent the car, of refrigerated air forced into the enclosure at great velocity and in great volume for dispersion throughout the articles located in the enclosure, and preferably returned through the same opening to the refrigeration apparatus for re-refrigeration and re-circulation through the enclosure.

One of my objects is to effect rapid and economical precooling of the articles in the enclosure; another object is to effect such precooling without dehydrating the articles when of such character that dehydration may occur in the precooling operation; and other objects as will be manifest from the following description.

Referring to the accompanying drawings:

Figure 1 is a cross sectional view of a refrigerator car and one embodiment of my improved apparatus associated therewith for precooling the contents of the car, the apparatus shown constituting one form of apparatus suitable for the practicing of my novel method of precooling, the section being taken at the line 1 on Fig. 2 and viewed in the direction of the arrow.

Figure 2 is a section taken at the line 2 on Fig. 1 and viewed in the direction of the arrow.

Figure 3 is a fragmentary plan sectional view of the structure of Figs. 1 and 2, the section being taken at the line 3 on Fig. 1 and viewed in the direction of the arrow.

Figure 4 is a cross sectional view, like Fig. 1, illustrating another embodiment of the invention and constituting another form of apparatus suitable for the practicing of my novel method; and

Figure 5, a fragmentary plan sectional view of the structure of Fig. 4, the section being taken at the line 5 on Fig. 4 and viewed in the direction of the arrow.

Referring to the construction shown in Figs. 1, 2 and 3, 6 represents a refrigerator car such as commonly provided and having the usual sidewall center door-openings 7 with the usual hinged door-closures one of which is shown at 8.

The car shown is of the type comprising a central refrigerating storage space 9 for the articles, with ice bunkers 10 at the ends of the car communicating at their upper and lower ends, through openings 11 and 12, with the storage space 9. The storage space 9 is shown as provided with an openwork false-floor 13 as commonly provided in cars of this type affording longitudinal channels 14 in communication at their ends with the lower openings 12.

In accordance with general practice the lading, to be refrigerated in accordance with my invention, provided in boxes or crates or other similarly shaped packages, and represented at 15, is stacked in the storage space 9 with the spacer-means between adjacent packages at different elevations and with vertical spaces between adjacent side-by-side disposed packages, to provide channels for air circulation throughout all sides of the packages 15.

The lading preferably occupies all of the space 9 except opposite the door openings thereby providing a cross aisle 16 extending from one door-opening 7 to the other and involves the use of bracing (not shown) in the aisle for preventing shifting of the lading in transit.

In accordance with this particular arrangement means are provided for forcing cooled air into the storage space 9 for cooling the lading and the flowing from the space 9 of the air heated in the operation of cooling the lading, the cooled air flowing through one portion of the door opening 7 at one side of the car and into the storage space 9 and the heated air flowing from this space 40 through another portion of this door opening, it being preferred that the air flowing from the storage space, in heated condition, be re-cooled and in such condition returned to the lading space and therein again utilized to further cool the lading, whereby the air flows through a closed circulatory course including the storage space 9, the inflow and outflow conduits and the course in which the air is re-cooled.

The means shown for conducting cooled air into the car and heated air therefrom comprises a conduit structure 17 shown as of accordian form and formed of flexible material, such as for example canvas, or the like, which connects at one end with one of the side door openings 7, substantially completely filling it and forming

therewith a closed joint to prevent leakage of air, and at its other end with the inlet and outlet of air-cooling apparatus represented generally at 18; the conduit structure 17 being provided with a substantially horizontal partition 18 shown as of flexible material, as for example canvas, or the like, dividing the conduit structure into upper and lower conduit sections 26 and 28, respectively, the end of the partition 18 adjacent the car being at substantially the same elevation as the upper surface of the lading as shown in Fig. 1.

The means for cooling the air to be forced into the storage space 8 may be of any desirable construction and provided as a stationary equipment of any desirable construction or, and preferably as portable equipment, such as that shown and provided for movement along the sides of the car to be cooled; this portable equipment, including in the particular apparatus shown the conduit structure 17, constituting a heat transfer unit.

The construction of cooling apparatus shown comprises a casing 22 mounted on a wheeled truck frame 23 and having three chambers 24, 25 and 26, the chambers 24 and 25 which constitute air-receiving and air-discharging chambers which communicate, respectively, with the upper and lower conduit sections 26 and 28, being separated by a refrigerating element represented at 21 and shown in the form of an open-work heat interchanger device through which any suitable refrigerating medium is circulated from any suitable source thereof through inlet and outlet pipes 29 and 30, respectively, and through which air entering the chamber 24 may flow in contact with the cooled surfaces of the refrigerating element 21 to become refrigerated and thence discharge into the chamber 25, a fan device 38 driven in any suitable way being provided in the chamber 25 for effecting such circulation of air.

To cause the cooled air supplied to the upper portion of the storage space 8 to be more nearly uniformly distributed throughout the lading and thus to more nearly effect uniform cooling of the lading, baffle means 31 preferably of a width substantially equal to the width of the car and of a length considerably greater than the cross-dimension of the cross-aisle 16 and positioned on top of the lading to span the cross-aisle and lap the lading at opposite sides of the aisle as shown are provided, the baffle means being shown as of sheet form, preferably of flexible material, as for example canvas or the like, connected at its ends with bar devices 32 of any suitable construction.

As will be understood from the foregoing, actuation of the fan 38 will cause air-flow as shown by the arrows, the air, cooled by the refrigerating element 21, preferably to a temperature slightly above freezing, as for example to about 34° F., entering the upper portion of the storage space 8 from the conduit section 28, thence dividing and flowing in opposite directions toward the ends of this space and thence downwardly and through the spaces between the articles to be refrigerated, flowing from opposite directions toward the center of the storage space and thence, in relatively heated condition by contact with the lading, to the lower conduit section 26, for recirculation, by the fan 38, through the refrigerating element 21, the operation above described being continued until the temperature of the contents of the storage space 75

has been reduced to the desired degree; following which the conduit structure 17 is disconnected from the car and the doors of the car quickly closed and sealed.

Preferably the cooled air is forced into the storage space 8 at a high velocity and great volume, as for example at a rate of approximately 60 M. P. H. and of such volume as to cause approximately 20,000 to 30,000 cubic feet of air per minute to flow into the storage space 8, whereby a substantially complete change of air in the storage space for the lading in the case of a car such as that above referred to, may be effected approximately every second during which the apparatus is in operation.

In accordance with one phase of my invention I provide for the intimate intermixture of relatively large quantities of refrigerated moisture with the cooled air supplied by the refrigerating apparatus to the car, before it contacts the lading, for the purpose of enhancing the refrigerating effect and so moistening the cold air that it will not act to dehydrate the lading when of such character that dehydration thereof would otherwise occur while undergoing refrigeration.

I accomplish this in the construction now being described by providing for the downward showering of refrigerated liquid, as for example water, in the storage space above the lading, into the cold air as it flows in this space to the lading. The means shown for this purpose comprise a header pipe 33 supported on the top of the lading (this pipe being preferably removable and replaceable in the car) and provided with upwardly directed showering spray heads 34.

The header-pipe 33 connects with any suitable source of liquid by a conduit 35 passing through the air conduit 17 and shown as formed of a rigid pipe section 36 and a flexible pipe section 37. The liquid in the arrangement shown is refrigerated as by passing it through a cooler 38 shown as located in the chamber 24. The cooler 38 may be of any suitable construction, that shown being of the standard shell and tube type, the liquid supplied to it, as for example from the ordinary service pipes, in case water is used as the liquid referred to, through a pipe 39 opening into one end of the shell 40 of the cooler and in communication with the tubes 41 in the cooler, the liquid passing through these tubes and into the opposite end of the shell 40 which opens into the pipe 35. Any suitable refrigerating medium, as for example refrigerated brine, is circulated through the intermediate portion 42 of the shell 40 and about the tubes 41 through inlet and outlet pipes 43 and 44 which would connect with any suitable source of the refrigerating medium.

The spray heads 34 would preferably be provided of such number and so spaced as to cause the cooled air in the top of the storage space 8 to be substantially uniformly charged with moisture.

The arrangement shown in Figs. 4 and 5, is the same as that shown in Figs. 1, 2 and 3 except that instead of spraying the liquid directly into the space 8, it is sprayed into the stream of cooled air as it passes through the upper conduit section 28. To this end spraying means, shown as involving two spray heads 45, are positioned in the conduit section 28 to direct sprays of the liquid substantially horizontally into the cool air flowing in this conduit, these spray heads being connected with a header 46 communicating with a pipe 47 opening into the shell 40 of the cooler as in the case of the pipe 35.

In both of the arrangements shown it is preferred that the refrigerated liquid to become mixed with the cool air as stated be supplied to the air at a temperature slightly above freezing, as for example at about 34° F.

In both of these arrangements such of the liquid as passes into the bottom portion of the storage space 9 discharges therefrom through a drain in the floor of this space. However, if desired, the liquid may be returned for re-refrigeration in the cooler 38 and recirculated in the system in any suitable way as will be understood by those skilled in the art.

If desired, all of the apparatus for producing the refrigerating medium to be supplied to the coolers may be mounted on the truck, as for example in the chamber 26 in the case of either of the arrangements shown.

In accordance with the preferred way of practicing my improved method, the refrigerated liquid and the refrigerated air are supplied simultaneously during the first part of the pre-cooling operation and the cooling of the lading finished by the use of cooled air only, particularly where it is desired that surface moisture produced on the articles during refrigeration be removed, though, if desired, such operation may be varied, as for example by utilizing the cooled air only (without liquid) during the first part of the operation of precooling the lading and thereafter supplying the cooled air and liquid, simultaneously to the lading.

The introduction of refrigerant liquid into the cooled air, as for example as shown and described, is of great practical value. The cold air forced into the storage space has a tendency to carry the moisture to otherwise inaccessible parts of the lading and therefore rapid cooling of the lading, due to direct contact of the cold liquid and the highly moistened air with the lading, is effected. Furthermore, the cooling action is caused to substantially uniformly act on the lading with the manifest advantage and fine regulation of the moisture content of the articles in the final refrigerated condition thereof may be effected.

While I have described certain procedures in the practicing of my improved method and have

disclosed certain forms of apparatus embodying my invention and adapted for use in performing my method, I do not wish to be understood as intending to limit it thereto as the method may be practiced in other ways and by other apparatus and the apparatuses disclosed may be variously modified and altered without departing from the spirit of my invention. Thus, by way of example, the air to be circulated through the lading may be refrigerated by ice stored in the ice bunkers of the car, with any suitable means for circulating the cooled air through the lading and the liquid for moistening the cool air refrigerated from a source beyond the car.

Also, as will be understood, my invention is not limited for use in connection with a brace-type of load as above referred to, as it has utility in connection with loads of the so-called squeeze type wherein the lading extends continuously across the aisle between the center doors at opposite sides of the car.

What I claim as new and desire to secure by Letters Patent, is:

1. The method of refrigerating perishable articles in an enclosure, comprising forcing refrigerated air into the enclosure for circulation therein against the articles and supplying liquid to the stream of air for mixture therewith during the first part of the refrigerating operation and forcing refrigerated air only into the enclosure during the latter part of the refrigerating operation.

2. The method of refrigerating perishable articles in an enclosure, comprising forcing refrigerated air into the enclosure for circulation therein against the articles during the first part of the refrigerating operation, and forcing refrigerated air into the enclosure for circulation therein against the articles and supplying liquid to the stream of air for mixture therewith during the latter part of the refrigerating operation.

3. The method of refrigerating articles in a refrigerator car having ice bunkers, which comprises supplying to the air circulating through the ice in the bunkers and in the storage space of the car, for mixture with the air, liquid from a source beyond the car.

HARRY Y. STEBBINS.
